UNITED STATES PATENT OFFICE.

JOHN F. O. STRATTON, OF CHICAGO, ILLINOIS.

FURNACE.

Original application filed August 28, 1925, Serial No. 52,998. Divided and this application filed August 28, 1925. Serial No. 53,000.

The present invention relates to improvements in furnaces, and has particular reference to furnaces of the type disclosed in my copending application Serial No. 52,998 filed 5 August 28, 1925, of which this application is a division.

In furnaces of the above type, a blast or jet of air is directed upwardly through the throat into the combustion chamber. 10 The blast of air agitates the fuel which is fed in at the top of the furnace, raises or holds it in suspension to secure complete combustion, and separates the combustible from the non-combustible portions. 15 To create this blast, air under pressure is admitted to the ash pit which serves as a pressure chamber, and from there passes through a long narrow space defined by a pair of parallel intercepting members directly underlying the throat. 20 In entering the ash pit, the air passes around the outside surfaces of the walls of the throat and through and over the intercepting members, and cools the same. The intercepting members are continuously reciprocated in unison to shift the region of the blast back and forth across the throat, thereby reaching all 25 portions of the fuel and keeping them in a mobile condition. The non-combustible portion of the fuel falls through the space between the intercepting members into the ash pit. A cleaning or slicing member is reciprocable on each intercepting member and oppositely thereto to remove slag and 30 fuel adhering thereto, and incidentally to stir and agitate the slag and fuel. The intercepting members are given a stroke substantially less in length than the width of the throat and in a range such that the 35 region of the air blast is always spaced from the side walls of the throat; and each slicing member is moved a substantial distance into the throat to the adjacent edge of the space as the latter is shifted in the opposite direction into its extreme position at 40 that side of the throat, thereby slowly moving the matter on the underlying intercepting member into the air blast.

The primary object of the present invention is to provide novel means for operating and adjusting the range of movement of the intercepting members and slicing members.

A further object resides in the provision

of means for independently adjusting the 55 range and extent of movement of each of the intercepting members and the slicing members, and for permitting independent manual operation.

Another object resides in the provision 60 of novel adjusting means for each movable operating member in which the angular position of the member is adjusted to adjust the effective component of its angular movement in a given linear direction. 65

Further objects and advantages will become apparent from the following description taken in connection with the accompanying drawings, in which:

Figure 1 is a vertical sectional view of 70 a furnace embodying the features of my invention.

Fig. 2 is a fragmentary enlarged sectional view taken along line 2-2 of Fig. 4.

Fig. 3 is a horizontal sectional view taken 75 along line 3-3 of Fig. 1 and showing the operating mechanism.

Fig. 4 is a sectional view taken partly in the plane of line 4-4 and partly in the plane of line 4'-4' of Fig. 1. 80

Fig. 5 is a fragmentary front view of a part of the operating mechanism.

While the invention is susceptible of various modifications and alternative constructions, I have shown in the drawings 85 and will herein describe in detail the preferred embodiment, but it is to be understood that I do not thereby intend to limit the invention to the specific form disclosed but aim to cover all modifications and alternative 90 constructions falling within the spirit and scope of the invention as expressed in the appended claims.

Referring more particularly to the drawings, while the main body of the furnace 95 may conform to any suitable construction, it preferably comprises a front wall 10, a rear or bridge wall 11, and inclined front and rear bottom walls 12 and 13, respectively. The space bounded by these walls constitutes a combustion chamber 14. Fuel, such as coal 15, may be continuously fed from a hopper 16 having a feed screw 17 through a spout 18 in a set off of the front wall 10 into the upper part of the combustion chamber 14. The front wall 10 is provided with an opening 19 having a closure 20, and through which fuel may be thrown into the

furnace by hand at any time. The inclined walls 12 and 13 are lined with suitable refractory material, such as bricks or blocks and converge to the upper edges of a long 5 narrow throat 21. The inclined walls serve to direct coal and slag falling thereon into the throat.

Located at the lower portion of the furnace and bounded by four walls 22, 23, 24 and 10 25 is an ash pit 26 which also serves as an air pressure chamber. Ashes may be removed from the pit 26 through an opening 27 in the wall 22 normally closed by the door 28.

The throat 21 is constructed of a plurality 15 of sections which fit closely together, and which preferably consist of blocks 29 shaped to form straight parallel side walls, and blocks 30 shaped to form curved end walls. The upper edges of the blocks 29 and 20 30 are curved or inclined, as indicated at 31, to form short continuations of the inclined walls 12 and 13, and the sides thereof extend vertically below said edges preferably for a distance of about six inches.

25 The blocks 29 and 30 are hollow metal castings capable of withstanding extremely high temperatures. Each side block 29 is formed with an air passage 32 having a downwardly extending nozzle 33 opening 30 into the ash pit 26 at the lower end of the throat. The outer wall of the nozzle 33 terminates a short distance above the inner wall to permit lateral deflection of the discharged air, surrounding the blocks 29 and 35 30 constituting the throat 21 is an air chamber 34 which communicates with the air passages 32. The air chamber 34 includes passages 35 around the end blocks 30 to connect the side spaces. In the present instance, 40 each passage 35 is constructed of an upper wall 36, a lower wall 37 and an end wall 38, the upper and lower walls extending up to the end blocks 30. Preferably the inner edge of the lower wall 37 is spaced a small 45 distance from the end blocks 30 to provide a narrow opening 39 adapted to permit the escape of a small amount of air for cooling purposes. One side of the air chamber 34 is connected to an intake conduit 40 of any 50 suitable shape adapted to receive compressed air from a suitable source (not shown). The inner walls of the blocks 29 and 30 are corrugated as shown to provide extensive outer cooling surfaces over which the incoming 55 air must pass, and to compensate for any variations due to expansion or contraction. Air entering the chamber 34 will be discharged through the nozzles 33 into the ash pit 26 to maintain a predetermined pressure 60 therein. The air cooled throat herein described is fully disclosed and claimed in my copending application Serial No. 52,999 filed August 28, 1925.

65 The air chamber 34 and throat 21 may be supported in any suitable manner, and in

the present instance are mounted at opposite ends on four channel shaped columns 41, the walls 36, 37 and 38 being rigidly secured thereto. These columns extend up from masonry columns 42 built in from the side 70 walls 24 and 25 of the ash pit 26.

Mounted on each of the columns 41 is one of a plurality of inwardly extending brackets 43 supporting a pair of parallel spaced tracks 44 and 45. Each track preferably 75 comprises two closely spaced parallel inverted T-shaped beams or bars. Movably mounted on the tracks are a plurality of anti-friction members, each of which consists of a pair of peripherally grooved sheaves 80 46 riding on the edges of the T-shaped beams and rigidly connected by a shaft 47. In the present instance, four anti-friction members, one on each end of each track are provided. Mounted for bodily reciprocation 85 on the friction members is a pair of tracks 48 and 49 each of which comprises two parallel bars connected together by means of spacers 50, and engaging the peripheral grooves in the sheaves 46. The front ends of 90 the bars of each of the tracks 48 and 49 are bent toward each other, and are connected by a pin 51 to which the rear end of an operating link 52 is pivotally secured.

Mounted on the tracks 48 and 49 for reciprocation therewith across the front portion of the throat is an intercepting member 53 which comprises a rectangular frame 54 having end brackets 55 rigidly secured to the tracks. A second intercepting member 58 having a similar frame 59 is mounted for reciprocation across the rear portion of the throat 21. The frame 59 however is not rigidly secured to the tracks 48 and 49, but is provided with end brackets 60 in which 100 rollers or sheaves 61 are mounted. The sheaves 61 engage the inner bars of the tracks 48 and 49 for adjustment toward and from the first mentioned frame. A plurality of grate bars 62 are mounted in the frames 54 and 59, and are formed with side lugs 63 to provide the usual spacing. The intercepting members 53 and 58 are spaced apart to define a long narrow space or passage 64 serving as a nozzle for directing a 110 blast of air from the ash pit 26 into the combustion chamber 14. To provide means for adjusting the width of the space 64, and for reciprocating the frame 59 with the tracks 48 and 49, the brackets 60 are formed 115 with upstanding lugs 65 to which the rear ends of two spaced adjusting links 66 are pivotally secured.

Two cleaning or slicing members 67 and 68 are provided for dislodging slag and other material adhering to or collecting on the intercepting members 53 and 58 respectively. The members 67 and 68 comprise a plurality of slicing grates 69, the free inner 125 ends of which are respectively reciprocable 130

in the front and rear sides of the throat and on the underlying grates 62 to and from the front and rear edges of the space 64, and the outer ends of which are formed with 5 hooks 70 fitting respectively over two horizontal shafts 71 and 72 extending along opposite sides of the throat. The front shaft 71 is mounted in the free upper ends of two spaced arms 73 pivotally mounted at their 10 lower ends on the front brackets 43 at opposite sides of the ash pit 26. The arms 73 are pivotally connected near their upper ends by means of studs 74 to the rear ends of two operating links 75. The rear shaft 72 is 15 similarly mounted on arms 76 supported by rear brackets 43 and pivotally connected by means of studs 77 to two operating links 78. The slicing grates 69 are formed with side lugs 79 to provide the usual spacing and are 20 dimensioned to extend beyond the sides of the throat 21 in all positions of reciprocation. The ends of the intercepting members and slicing members also extend beyond the ends of the throat 21. The grates 62 and 69 25 permit small amounts of cold air to percolate through the intercepting members and slicing members to cool the latter and to cause the slag falling thereon to harden. While grates preferably are employed, it is 30 to be understood that any other suitable means having small openings for the passage of air may be employed.

To prevent fuel or slag from being carried on the grates 69 out of the throat 21, a plurality of scraper members 80 are provided. In the present instance, four scraper members are provided, and each member comprises a bar 81 extending along one half of one side and curved partially around one end 40 of the throat 21, and a pair of spaced arms 82 pivotally secured in brackets 83 on the under side of the air chamber 34. The bars 81 rest on the grates 69 directly beneath the nozzles 33, and each bar is formed with an 45 upstanding flange 84 for deflecting part of the air from the nozzle overhead outwardly over the surfaces of the grates 69. Air thus passes over and through the grates 69 to cool the latter.

50 The front ends of the links 52, 66, 75 and 78 are pivotally connected to four pairs of levers 85, 86, 87, and 88 mounted on four shafts 89, 90, 91 and 92 respectively. These shafts extend transversely in the front of the 55 ash pit 26, and through air tight bearings 93 in the side wall 25 into a chamber 94 open at the top to the atmosphere, and are journaled in spaced bearing brackets 95 and 96 in opposite sides of the ash pit and in a bearing bracket 97 in the chamber 94. The levers extend upwardly from the shafts so as to have a horizontal throw, and are subject to adjustment as will be hereinafter described. Secured to the ends of the shafts 60 89, 90, 91 and 92 in the chamber 94 are four

substantially horizontally disposed levers 98, 99, 100 and 101 respectively which are pivotally connected to the lower ends of four links 102, 103, 104 and 105 respectively, extending vertically through a hole 106 in the floor 107 at the front of the furnace. The levers 98 and 101 extend forwardly, and the levers 99 and 100 extend rearwardly so that upon movement of the links 102, 103, 104, and 105 in like directions, the intercepting members and the slicing members will be reciprocated in opposite directions.

At their upper ends, the links 102, 103, 104 and 105 are adjustably attached respectively to four horizontally extending sector plates 108 formed in parallel spaced relation on a plate 109 pivotally mounted in a supporting standard 110. Each sector plate 108 is formed with an arcuate slot 111 in which a bolt 112 is adjustably mounted. One end of the bolt 112 is pivotally secured to one of the links 102, 103, 104 and 105, and the other end is provided with a hand wheel nut 113 for clamping the bolt in adjusted position in the slot 111. The bolt is also provided with a hand lever 114 whereby it may be moved in the slot 111 when the nut 113 is loosened either to effect an adjustment or to manually operate the associated link. It will be evident that by adjusting the vertical links, the levers on the horizontal shafts in the ash pit 26 will be adjusted angularly, thereby changing their position and also changing the horizontal or effective component of their throw for a given angular movement. The plate 109 is formed with a downwardly extending arm 115 which is connected through a link 116 to a crank arm 117 of a reduction gearing 118 driven by any suitable means (not shown).

The adjustment is such that the frame 59 is reciprocated through substantially the same distance as the tracks 48 and 49 to maintain the space 64 at a fixed width throughout the operation. The space 64 is 110 shifted only across the central area of the throat, and the slicing members are periodically projected a substantial distance into the throat to meet the space at a substantial distance from the sides. The throat is constructed of a width permitting however a substantial movement of the space 64.

In operation of the furnace, crushed fuel 115 is charged into the furnace from the spout 18 in the form of a falling stream. 120 The fuel may be initially ignited in any well known manner as by the use of gas jets or other equivalent devices.

Air enters through the conduit 40 into the air chamber 34, a portion of the air passing downwardly through the adjacent nozzles 33 in the side blocks 29, and the remaining portion passing around the end blocks 30 to the nozzles 33 on the remote side of the throat 21. A small amount of air also 125

passes through the end openings 39 into the ash pit. Part of the air discharged from the nozzles 33 passes through the spaces between the grates 62 and 69, and part is laterally deflected by the scraping members 80 to pass over the surfaces of the grates 69, into the ash pit 26, thereby cleaning and cooling the grates. From the ash pit, the air is forcibly discharged in the form of a blast through the space 64 between the intercepting members 53 and 58 into the combustion chamber 14. The blast of air expands and tends to hold the fuel in suspension. The course of the air is indicated in the drawings by arrows.

The fuel is consumed while in suspension. Parts of the fuel fall on the inclined walls 12 and 13, and are directed thereby into the throat 21. Molten slag runs down the inclined walls into the throat and onto the grates 62 and 69. The slag there is caused to solidify by the relatively cold air percolating up through the spaces between and cooling the grates. The non-combustible material has a greater specific gravity than the incandescent and partially volatilized combustible material. A pressure is maintained in the ash pit such that the force of the blast of air will allow the non-combustible material to fall through the space 64 into the ash pit, and will retain the combustible material in suspension. The width of the space 64 between the intercepting members can be adjusted by adjusting the connection between the link 103 and the associated sector plate 108, and the range of reciprocation can likewise be adjusted by adjusting the links 102 and 103 relative to the sector plate. After adjusting the width of the space 64 in a definite position in the throat, its width may vary in the reciprocation due to different angular positions of the arms 85 and 86.

The intercepting members 53 and 58 are reciprocated to shift the region of the blast of air slowly back and forth across the throat, but not to the very sides of the throat. By shifting the region of the blast of air all parts of the fuel in the furnace are reached. The slag and fuel on the grates 62 are dislodged and moved into the blast of air by the slicing grates 69 which are reciprocated oppositely to the members 53 and 58, thereby cleaning the grates and also agitating the material to permit efficient separation. The reciprocation of the slicing members is continual and at a sufficient speed to prevent a large mass of material from collecting on the grates. Each slicing member is moved substantially out of the throat on its outward stroke to clean the same, and this cleaning is facilitated by means of the slicing members 80. By cleaning the grates 62 and 69 efficient cooling is permitted. The range and extent of reciprocation of the slicing grates can be ad-

justed through the links 104 and 105. Adjustments are preferably made with the slicing member in the desired innermost positions. Upon loosening the nuts 113, the above parts can be selectively operated manually by means of the hand levers 114.

It will be evident that I have provided an efficient vertical jet combustion furnace capable of fine adjustments to suit different operating conditions, and not likely to get out of order.

I claim as my invention:

1. In a furnace, in combination with a combustion chamber having a throat in the bottom thereof, an air pressure chamber below said throat, and intercepting means consisting of a pair of sections interposed between said pressure chamber and the lower end of said throat, said sections being spaced apart to define a nozzle for directing a blast of air from said pressure chamber through said throat into said combustion chamber, means for reciprocating said sections back and forth across said throat to shift said blast, and means for adjusting said last mentioned means to selectively adjust the movement of each of said sections, said adjusting means being manually operable to reciprocate said sections manually.

2. In a furnace, in combination with a combustion chamber, a throat in the bottom of said combustion chamber, an air pressure chamber below said throat, and intercepting means disposed across said throat, said intercepting means consisting of a pair of spaced apart sections for directing a blast of air from said pressure chamber into said combustion chamber, means for reciprocating said sections in unison to shift said blast back and forth across said throat, and means for adjusting said last mentioned means to adjust the width of the space between said section and to adjust the extent and range of the reciprocation of each section.

3. A furnace having, in combination, a combustion chamber having an opening in the bottom thereof, a pair of intercepting sections positioned across said opening, a pair of slicing members positioned on said intercepting members, and a single means for reciprocating said intercepting members and said slicing members in opposite directions.

4. A furnace having, in combination, a combustion chamber having an opening in the bottom thereof, a pair of intercepting sections positioned across said opening, a pair of slicing members positioned on said intercepting members, and a single means for reciprocating said intercepting members and said slicing members in opposite directions, said means being adjustable to individually adjust the movement of each member.

5. A furnace having, in combination, a combustion chamber having an opening in the bottom thereof, a pair of intercepting sections disposed across said opening, means for reciprocating said intercepting sections in unison, means for adjusting said last mentioned means to change the movement of either of said sections, means for locking
- 10 said adjusting means in adjustment, said last mentioned means when released permitting said adjusting means to be used for reciprocating said sections manually.

In testimony whereof, I have hereunto affixed my signature.

JOHN F. O. STRATTON.
